CLAIM

The ornamental design for the tri-paddle bit, as shown and described.

DESCRIPTION

FIG. 1 is a perspective view of a tri-paddle bit in accordance with an embodiment of the present invention;

FIG. 2 is a left side view of the tri-paddle bit of FIG. 1;

FIG. 3 is a right side view of the tri-paddle bit of FIG. 1;

FIG. 4 is a top view of the tri-paddle bit of FIG. 1;

FIG. 5 is a bottom view of the tri-paddle bit of FIG. 1;

FIG. 6 is a front view of the tri-paddle bit of FIG. 1; and,

FIG. 7 is a rear view of the tri-paddle bit of FIG. 1.

The broken lines of FIGS. 1-7 are illustrative of portions of the tri-paddle bit that form no part of the claimed design.

1 Claim, 6 Drawing Sheets
